UNITED STATES PATENT OFFICE.

MELVILLE E. PETERS, OF DENVER, COLORADO.

PNEUMATIC DEVICE FOR FEEDING FINISHING-BLANKS TO BOX-COVERING MACHINES.

1,149,405.

Specification of Letters Patent. Patented Aug. 10, 1915.

Application filed April 20, 1914. Serial No. 833,295.

To all whom it may concern:

Be it known that I, MELVILLE E. PETERS, a citizen of the United States of America, residing at the city and county of Denver and State of Colorado, have invented a new and useful Pneumatic Device for Feeding Finishing-Blanks to Box-Covering Machines, of which the following is a specification.

My invention relates to a pneumatically operating method and apparatus for feeding box covering and finishing blanks to box covering machines, and the objects of my invention are, first, to provide a pneumatically operating method and apparatus for feeding gummed finishing blanks from a supply of the same, into the unfinished box or box blank receiving center of a box covering machine; and second, to provide a simple, quick acting and positively operating blank feeding method and apparatus for box covering machines.

I attain these objects by the mechanism illustrated in the accompanying drawings, in which:

Figure 1 is a vertical sectional view through a portion of a box covering machine, showing my improved mechanism for transferring box covers from a receiving table to a platen, in position to be secured upon boxes. Fig. 2 is a plan view of a portion of the mechanism shown in Fig. 1. Fig. 3 is a rear end view of Fig. 1. Fig. 4 is a side view of the cam and parts actuated thereby, for reciprocating the rod which carries the suction box. Fig. 5 is a side view of the cam and levers connected therewith, which effect a quarter rotation of the reciprocating rod which carries the suction box. Fig. 6 is a vertical, longitudinal, sectional view of the pump for exhausting air from, and admitting air to, the suction box. Fig. 7 is a side view, partly in section, of the suction box for transferring the box covers from a receiving table to the platen. Fig. 8 is a vertical, transverse, sectional view through the rear bearing of the supporting rod for the suction box. Fig. 9 is a vertical, longitudinal, sectional view through the same. Fig. 10 is a vertical, transverse, sectional view through the forward bearing for the suction box supporting rod; and Fig. 11 is a plan view, partly in section, showing the rear portion of the suction box supporting rod, the sleeve $\diamond 1$ the end thereof, and the link which connects the said sleeve with the operating lever.

Similar letters of reference refer to similar parts throughout the several views.

Referring to the drawings, the numeral 1 designates a fragmentary part of the frame of a paper box covering machine. My invention can be used in connection with any machine in which finishing paper or other suitable finishing material blanks are used to cover paste-board boxes, or with machines used to assemble them either partially or wholly together jointly with the finishing blanks.

In the practical application of my invention, it is necessary that some means be provided for gumming the blanks; that is, of applying a coat of glue or other adhesive material to them, and this coat of gum or glue may be applied to the whole of one side of each blank or to only a part or portion of one side of each blank. This feature of my invention can be carried out by applying the gum by hand or by any of the blank gumming machines at present in use in the art of making paper boxes, and there are a number of machines at present in use for this purpose, which can be used with my invention.

I do not illustrate a means of applying an adhesive material to the blanks, as such means does not form a part of my present invention. It is understood, however, that the blanks are preferably gummed, and are transferred from the gumming means to the table 2, one at a time, and are placed by an attendant or by mechanical means, against the registering plates 3, which are adjustable in slots 3^A , formed in the table, that are arranged to receive clamping screws 3^B in such a manner that the plates can be adjustably set in positions that will enable an attendant to register different sized blanks centrally on the table and in position to allow one of its sides to extend beyond the inner edge 3^C , of the table 2, ready to be seized and gripped against the surface 4, of an air impulse device 5, which is operated by suitably air actuating mechanism. This air actuating mechanism may be located apart from the machine to which my blank feeding mechanism is attached, if desired. I preferably, however, use and illustrate an air pump for actuating air to grip and release the blanks at their registering points, and illustrate this air pump attached to the frame of the machine and arranged to be driven by power transmitting mechanism.

which, with the pump, I will describe hereinafter.

The box covering machines at present in use comprise a frame 1, a fragment of which I illustrate, a platen 7, to which the blanks are fed and on which they are deposited at what is termed a registering point, and also to which the paste-board box covering blanks or made-up paste-board boxes, as the case may be, are fed, and on which they are also deposited, either directly, or first onto a form block 8 that normally stands above the platen and by which almost instantly afterward the paste-board box, or paste-board blank, as the case may be, is moved down on top of and against the finishing blanks, and instantly afterward the finishing paper and paste-board box or the paste-board blanks together are fed into the box covering mechanism, and which acts to fold the blanks around the made-up box or to fold the two blanks, as the case may be, up into finished boxes. My present invention, however, has nothing to do with the mechanism that wraps the covering and finishing blank around a stayed cornered or an unstayed cornered box, or that is intended to be folded up with a blank piece of paste-board cut to be formed into a paste-board box, as the case may be, my present invention being limited to a pneumatic method of feeding a gummed blank from a registered position or a table 2, adapted to receive it from a gumming machine, to a predetermined registering position on the platen of a box covering machine where the blanks are positioned to receive the boxes that are to be covered. To this end, my invention in the preferred form in which I have illustrated it, consists of a bar 9, preferably a square bar, which is supported in bearings 10 and 11 that are attached to the box covering machine in any suitable manner. This bar 9, is a square reciprocating bar and is consequently slidably mounted in the bearings 10 and 11. It is also necessary that it turn or oscillate through a part of a full revolution on its longitudinal axis, and in order that it may accomplish both a longitudinal and a partial rotative or oscillating movement on its axis in its supporting bearings, I arrange these bearings in the following manner: The bearing 10 comprises a bracket 12, that is detachably secured to the frame 1, of the box covering machine. The free end of this bracket is provided with a capped journal box 13, in which a sleeve 14 is rotatably mounted, and this sleeve is provided with a square axial aperture 15, through which the square bar 9 extends slidably, while the bar and sleeve are free to rotate or turn through a part of a full revolution, which I preferably limit to a quarter of a revolution, as will be hereinafter fully described. The bearing 11, comprises a

capped journal box 16, that projects from a bracket portion that is detachably secured to or forms an integral part of the frame 1, and this capped journal box is arranged to receive rotatably the hub portion 17, of a bevel gear 18, which extends loosely through and beyond it and is provided with a collar 19, at its end, which is secured to it by a pin 20, or other suitable means. The bevel gear is provided with a square shaped axial aperture through which the bar 9 extends loosely and slidably, and it is this gear which effects through another gear 21 and other co-operating mechanism, the quarter turning or oscillating movement of the square bar 9. This gear 21 is supported in mesh with the gear 18 and at right angles to it in a capped bearing 22, which is formed in a bracket 23, that is detachably secured to the frame 1. The hub 24 of this gear 21 extends beyond this bearing and its end is provided with a projecting lever 25, the outer end of which is pivotally secured by a pin 26, to one end of a lever 27. This lever 27 is pivoted at its opposite end by a pin 28 to one end of a rock arm 29, the opposite end of which is pivotally connected to the frame 1 by a pin 30. This rock arm is provided at the center of its arm with a roller 31, which is arranged to project into a cam groove 32 formed in a cam 33, which is mounted on a driving shaft 34, that is journaled in suitable bearings 35, which are positioned on the frame. The cam imparts sufficient movement to the rock arm 29 and the lever 27, to cause the gear 21 to turn a quarter of a revolution, which rotary movement is imparted to the gear 18, and it is turned a quarter of a revolution and it turns the square bar 9 a quarter of a revolution, and as it does so, it turns an adjustable bracket 36, which is slidably mounted on the opposite end of the bar 9. This adjustable bracket 36 is slidably mounted on the square bar 9 and is secured thereon in adjusted positions by a set screw 37, and it supports at its free end the air impulse device 5, that grips the blanks and conveys them to the platen 7 of the box covering machine, and releases them at a point where the boxes will register on them. This air impulse box will be described hereinafter.

The rear end of the square bar 9, extends a short distance beyond the bevel gear, and to its end a sleeve 38 is rotatively secured. This sleeve 38 is rotatively mounted on a reduced round shouldered portion 40 that is formed on the terminal end of the square bar 9, and from opposite sides of the sleeve, project screws 41, which receive the ends 42 of the yoke-shaped lever 43, which forms one end of a link, the opposite end of which is also provided with a yoke-shaped end that straddles one end of a crank lever 45. This crank lever is pivotally supported in

termidate of its ends, by a pin or bolt 46, to a part of the frame 1, while its opposite end is pivotally secured to one end of a yoke lever 47, the opposite end of which is provided with a forked end 48 that extends to and straddles the driving shaft 34, which acts as a support for the forked end of this lever, and permits it to slide reciprocally thereon. This forked lever is provided with 10 a roller 49, which is secured to it intermediate of its ends, by a pin 50. This roller is arranged to project into a cam groove 51, formed in a cam disk 52, which is mounted on and is secured to the driving shaft 34, and is arranged to impart a reciprocal throw stroke to this forked lever and to the crank lever 45 connected to it and to the link 43, to impart an intermittent reciprocal stroke movement to the square 20 bar 9, while the sleeve 38 permits the bar 9 to be turned through a quarter of a revolution on the inoperative stroke of its reciprocal movement, as will be fully described hereinafter.

25 The driving shaft may be rotated by belt or gearing which may be secured to and driven by any suitable motive power. I have preferably illustrated, however, this shaft provided with a worm gear 53 which 30 is mounted on and secured to it. This worm gear meshes with a worm pinion 54. This worm pinion is mounted on a short counter-shaft 55, that is supported in a suitable bearing 56, that is secured to the frame and 35 upon which a belt receiving pulley 58 is also mounted and secured, which may be connected by a belt with any suitable motor or rotary power transmitting mechanism.

It is essential that the bracket 36 at the 40 forward end of the bar 9, have a quarter turn movement on its backward or inoperative stroke of its reciprocal movement, in order that the air impulse box at its end may pass by the form block 8, of the box 45 covering machine, because the form block moves immediately down against the platen the instant after a finishing blank has been deposited at the box registering point of the platen 7, and this form block is consequently in the path of the return movement 50 of the outer end of the air impulse box. Consequently the square bar 9, is positioned far enough to one side of the form block 8, to entirely clear it on its reciprocal 55 strokes, but it is necessary that the air impulse device at its free end be arranged so that on its operative blank moving stroke it will move centrally underneath the form block 8, in order that it may deposit the finishing blanks centrally underneath it, inasmuch as the paste-board box that the finishing blank is to cover, is either placed first on the form block, or is fed directly on top of the finishing blank instantly after 60 it is deposited on the platen. Consequently,

in order that the air impulse box may avoid contact with the form block 8, on its back stroke, the air impulse device must be moved to one side of the form block at the time it starts to move on its backward stroke to grip another blank, and this form block clearing movement of the air impulse device is accomplished by causing the bracket to turn from the downward vertical position it stands in when the air impulse box is in 70 air gripping relation to the blanks, to a horizontal position, which change of position it accomplishes by being moved through a quarter circle turning movement by the bar 9, which quarter turning movement turns the air impulse device also from the horizontal position in which it receives and grips the finishing blank, and moves it over to and deposits it on the platen and continues to the end of its operative stroke, 80 at which point it is swung up and changed from its operative horizontal position into a vertical position before it starts back on its backward stroke, which moves it out of the path of the form block and allows it to 85 pass the form block 8 on its return backward and inoperative stroke. When, however, it has passed the form block 8, and before it reaches the end of its backward stroke, it is again turned down into its horizontal position and completes the remainder 90 of its stroke in that position and moves under at the end of its backward stroke another finishing blank which the air impulse draws down against it with a gripping force 95 that holds it firmly to it, after which it again starts on its operative blank feeding stroke and moves it over onto the platen 7, and thus repeats the cycle of its reciprocating movement; and these two quarter turning movements of the bar 9, its bracket 36, and the air impulse blank gripping device are accomplished by the gears 18 and 21, and their coöperating levers and the cam 33, while the rod 9 is being moved on its 100 backward stroke by the cam 52, and its connecting levers and the trunnion sleeve, as 110 will be fully explained hereinafter.

The pneumatic impulse device that grips and moves and releases the blanks in alternate order from their gummed location to a predetermined position on the platen 7 where the boxes to be covered will register on top of them, may be made in a number of ways, but as illustrated, it preferably comprises a hollow chambered member, which I preferably illustrate in the form of a hollow rectangular box, and which I will term the air impulse box. This air impulse box is provided with a row of air inlet and outlet apertures 57, that are arranged to extend through its top surface 4, adjacent to its front end, and they extend across its width. This air impulse box is made wide enough 125 to grip the largest size blanks that are to 130

be used, and when blanks are used that are of smaller size than the largest size blanks used, the air holes in the box outside of these smaller or narrower blanks can be closed by pasting pieces of paper over them.

The air box is preferably made to feed blanks for boxes of different sizes ranging from about $13\frac{1}{2}$ by $20\frac{1}{2}$ inches square, down to boxes of about $1\frac{1}{4}$ by $3\frac{1}{4}$ inches square.

10 The table 2 upon which the blanks are placed and registered to be gripped by the air impulse box, is adjustably and slidably mounted on a supporting frame 59, by means of a bracket 60, that allows it to be moved 15 and adjustably set by any suitable means toward or away from the platen 7, of the box covering machine, to accommodate it to receive small or large size finishing blanks in a registering position that will permit 20 them to be gripped by the air impulse box, and the bracket 36, is likewise adjustably set on the bar 9, by a set screw 37, to any position desired to adjust the air impulse box to small or large finishing blanks. As 25 illustrated, the top of the frame is provided with a bolt receiving slot 62, on which the bracket of the table is arranged to slide and which is arranged to allow the heads of the bolts to clamp against the side surfaces of 30 the slot, and bolts 63, having properly shaped heads 64, fit into the slots and clamp the bracket 60, of the table to the top of the frame in adjusted positions. This air impulse box 5 preferably forms an integral 35 part of the bracket 36 and projects from its lower end and stands at right angles to it, and when in an operative blank moving position stands in a horizontal plane, while the bracket stands in a vertical plane. This 40 air box is provided with an entrance aperture at its bracket end, and a pipe nipple 65 is secured to it. An elbow 66 is threaded to the nipple, and to the elbow a nipple 67 is threaded, and to this nipple 67 one end 45 of a piece of hose 68 is secured. This hose extends to and is secured to one end of a pipe 69, the opposite end of which is secured to the air actuating end of an air pump 70, which is preferably mounted on the frame 1 50 of the box covering machine in a position to be driven from the driving shaft 34 of the machine. This air pump comprises a cylinder provided with one closed end 71, and one open end 72, and in the cylinder 55 a suitably packed piston head is reciprocally mounted, from which a short piston rod 73 extends, to which one end of a connecting rod 73^A is pivoted, through the end 60 of the cylinder, and at its outer end it is pivotally connected to one end of a rock arm 74; the opposite end of the rock arm is pivotally connected to the frame 1. This rock arm 74, is also pivotally connected to one 65 end of a forked lever 75, the opposite end 75^A, of which is forked, and straddles the

driving shaft 34 slidably. This forked lever is provided intermediate of its ends with a laterally projecting roller which projects into a cam slot 76, that is formed in a cam disk 77 which is mounted on and is secured to the driving shaft 34. This cam slot 76, the forked lever 75 and the rock arm, act under the rotative action of the driving shaft to reciprocate the connecting rod, the piston rod and piston head in the cylinder.

The operation of my pneumatically operating method and apparatus for feeding box covering and finishing blanks to box covering machines, is as follows: Power 80 from any suitable source having been applied through the medium of a belt to the pulley 58, a rotary motion is imparted to the driving shaft and the cams 33, 52 and 77, through the worm gearing. An attendant then having placed a blank against the registering plates on the table 2, which forms the blank starting and registering station, in which position one side of it will hang over the end of the table 2, and assuming that the air box is in position under the adjacent over-hanging side of the blank, then an outward stroke of the piston head and its rods, due to the rotary movement of the cam 77 and the oscillating movements of the forked lever 75, and the rock arm, will cause an air suction force in the closed end of the air pump cylinder, which draws air into the air apertures 57, in the top surface 4 of the box 5, and as these air apertures are directly under the blank, the suction force of the air draws the over-hanging side of the blank down tight against the top surface of the box over and against the entrance of the apertures of the air suction box. This grips with a drawing suction action the side edge of the blank against the surface of the box. This suction action takes place the instant the piston head starts on its outward stroke, and instantly afterward the cam 52, through its rotary movement, causes the forked lever 47 and crank lever 45 to pull and move the square rod 9 on the operative stroke of its reciprocal movement, which operative stroke moves the air box with the blank still held to it by the force of the suction, over and onto the top of the platen 7, where, at a predetermined registering point, the cam 77 and levers 74 and 75 are arranged and timed in their action to instantly reverse the direction of movement of the piston head, which action instantly breaks the suction force on the blank and exerts a slight outward jet of air from each aperture, which frees the blank instantly from the box and allows it to rest on the platen while the air box continues to the end of its stroke, which is long enough to convey it out of the path of the form block 8 of the box covering machine. It will thus be seen that the suction 95 100 105 110 115 120 125 130

action of the pump is timed to be continuous from the time it grips a blank until the blank is fed over onto the platen 7, where it is instantly released by the breaking of the 5 suction force, which takes place the instant the outward stroke movement of the pump is reversed, and the piston head of the air pump starts on its inward stroke, which is an air compression stroke, and drives the 10 air, if any, out of the cylinder and out of the hose and air box. Thus suction force action, as well as the outward pressure flowing action of the air under the action of the air pump, is an air impulse action; as the 15 blank moving stroke of the air box is a quick stroke, the cam and levers that actuate the rod 9 and the air box being arranged to move the air box quickly over the platen from the table; consequently but a second or two or 20 but a fraction of that time is required in which the air suction box grips and moves a blank from the registering table 2, to the platen. Having arrived at the end of its blank feeding stroke, the air impulse box 25 is instantly turned and swung up from its horizontal position to an edgewise vertical position by the cam 33, and levers 29 and 27, which action moves the air impulse box through an arc of a quarter of a circle and 30 swings it laterally to one side of and out of the path of the form block 8, and the instant the cam and its levers again act to move the box backward on its return or inoperative stroke past the form block, and 35 after it has passed the form block, and before it reaches the end of its backward stroke, and while it is still moving, the cam and levers actuate the bevel gears to swing it down and back into its normal horizontal position, in which position it completes its 40 backward stroke and moves up to the adjacent edge of the table 2, and under the overhanging side of another blank, thus completing the cycle of its reciprocal blank 45 gripping, feeding and depositing movement.

My invention provides a simple, quick-acting, reliable feeding apparatus for feeding box covering and finishing blanks to box covering machines, and while I have illustrated and described the preferred construction and arrangement of my invention, I do not wish to be limited to the construction and arrangement shown, as many changes might be made without departing from the 55 spirit of my invention.

Having described my invention, what I claim as new and desire to secure by Letters Patent, is:

1. In a blank-feeding device for box-covering machines, the combination of a blank registering table, a platen, a box-forming member coöperating with said platen, a blank gripping device for feeding the blanks from said table to said platen, means for 60 moving said gripping device from said table

to said platen and return, said gripping device passing between the box-forming member and the platen on its forward stroke, and means for moving the gripping device to one side of the platen and the 70 box-forming member on its return stroke.

2. In a blank-feeding device for box-covering machines, the combination of a blank-registering table, a platen, a box-forming member coöperating with said platen; a reciprocating rod, a pneumatic blank gripping device carried by said rod for feeding the blanks from said table to said platen, means for moving said gripping device from said table to said platen and return, said gripping device passing between the box-forming member and the platen on its forward stroke, means for moving the gripping device to one side of the platen and the box-forming member on its return stroke, and 80 means for alternately creating a suction and a pressure in said pneumatic device.

3. In a box-covering machine having a frame, a reciprocating rod mounted in bearings on said frame, a blank-gripping device 90 adjustably mounted on one end of said rod, means for reciprocating said rod comprising a yoke lever connected to the other end of said rod, a bell-crank link pivoted in the frame and connected to said yoke lever, a driving-shaft having a cam mounted thereon, and a cam lever connected at one end to said bell-crank lever, and at the other end coöperating with said cam.

4. In a box-covering machine having a frame, a reciprocating rod mounted in bearings on said frame, a blank-gripping device adjustably mounted on one end of said rod, means for partially rotating said reciprocating rod during one of its strokes comprising a hub rotatably received in one of the bearings for said rod, said hub having a squared aperture through which said rod passes, a bevel gear on one end of said hub, a second bevel gear meshing with the first bevel gear, a crank connected to said second bevel gear, a bell-crank lever, a link connected at one end to said crank and at the other end to said lever, said lever being pivoted in the frame, a cam roller intermediate the ends of said lever, a driving shaft having a cam mounted thereon, said cam co-operating with said cam-roller to actuate said lever.

5. In a box-covering machine having a frame, a reciprocating rod mounted in bearings on said frame, a blank-gripping device adjustably mounted on one end of said rod, means for reciprocating said rod comprising a yoke lever connected to the other end of said rod, a bell-crank lever pivoted in the frame and connected to said yoke lever, a driving shaft having a cam mounted thereon, a cam lever connected at one end to said bell-crank lever, and at the other end co- 120 125 130

6
operating with said cam, and means for partially rotating said rod during one of its reciprocating strokes.

6. In a box-covering machine having a frame, a reciprocating rod mounted in bearings on said frame, a blank-gripping device adjustably mounted on one end of said rod, means for reciprocating said rod, means for partially rotating said reciprocating rod during one of its strokes comprising a hub rotatably received in one of the bearings for said rod, said hub having a squared aperture through which said rod passes, a bevel gear on one end of said hub, a second bevel gear meshing with the first bevel gear, a crank connected to said second bevel gear, a bell-crank lever, a link connected at one end to said crank and at the other end to said lever, said lever being pivoted in the frame, a cam-roller intermediate the ends of said lever, a driving shaft having a cam mounted thereon, said cam coöperating with said cam-roller to actuate said lever.

7. In a box-covering machine having a frame, a reciprocating rod mounted in bearings on said frame, a blank-gripping device adjustably mounted on one end of said rod, means for reciprocating said rod comprising a yoke-lever connected to the other end of said rod, a bell-crank lever pivoted in the frame and connected to said yoke lever, a driving shaft having a cam mounted thereon, a cam lever connected at one end to said bell-crank lever, and at the other end co-operating with said cam, means for partially rotating said reciprocating rod during one of its strokes comprising a hub rotatably received in one of the bearings for said rod, said hub having a squared aperture through which said rod passes, a bevel gear on one end of said hub, a second bevel gear meshing with the first bevel gear, a crank connected to said second bevel gear, a bell-crank lever, a link connected at one end to said crank and at the other end to said lever, said lever being pivoted in the frame, a cam-roller intermediate the ends of said lever, a driving shaft having a cam mounted thereon, said cam coöperating with said cam-roller to actuate said lever.

8. In a machine of the character described, a rod, a suction device mounted on said rod, means for reciprocating said rod, means for imparting a quarter rotation to said rod at the limit of its rearward stroke and for reversing its rotation at the end of its forward stroke, and means for exhausting air from and admitting air to said suction device at predetermined intervals.

9. In a pneumatically operating blank feeding apparatus for box covering machines, in combination, an adjustable blank registering table for receiving said blank, arranged and adapted to register said blank

fed to a box covering machine, with the blank receiving platen below the form block of a box covering machine, and with means including an air impulse device for moving said blanks from said blank registering table to the said platen of said box covering machine, said means comprising a reciprocal movement mechanism adapted to move said air impulse device from its registering station on said table to said platen, and between it and said form block on the blank feeding stroke of its reciprocal movement, and arranged and adapted to move to one side of said form block on the backward stroke of its reciprocal movement, and means for effecting said reciprocal movement.

10. In a pneumatically operating apparatus for feeding blanks to box covering machines, the combination of the adjustable blank receiving and registering table arranged to be placed adjacent to a box covering machine, and arranged to register blanks with a portion projecting beyond the end of the table closest to said box covering machine, said box covering machine being provided with a blank receiving platen and a reciprocating form block arranged to move against said platen, an air impulse device arranged to grip said projecting portion of said blank at said table, reciprocal means for moving said air impulse device from said table between said platen and form block on one stroke of its reciprocal movement, and means for turning said air impulse device to one side of said form block on its backward stroke and for returning it into its blank gripping position after it has passed the form block and before it completes the rearward stroke of its reciprocal movement.

11. In a pneumatically operating apparatus for feeding blanks to box covering machines, the combination of the adjustable blank receiving and registering table and the box covering machine provided with a platen and form block, and a driving shaft, the bar reciprocally mounted on said box covering machine, the air impulse box mounted on one end of said bar and arranged to be moved reciprocally to and from said table and platen and to grip, feed and deposit blanks registered on said table onto said platen, a swiveling connection at the opposite end of said reciprocating bar from its air impulse box supporting end, a link pivotally connected at one end to said swiveling connection and pivotally connected at its opposite end to a crank arm, said crank arm being pivotally connected intermediate of its ends to said machine and at its opposite end to a forked lever, the opposite end of which is forked, and straddles the driving shaft of said machine, said forked lever being provided with a roller intermediate of

its ends and a cam mounted on said driving shaft of said machine and provided with a cam groove arranged to be engaged by said roller, said cam and forked lever and cam lever being so relatively arranged and adapted to impart a reciprocal stroke movement to said reciprocal movement bar of sufficient throw to cause said air impulse box to operatively feed blanks from said table to the blank receiving platen of said machine.

12. In a pneumatically operating apparatus, for box covering machines, the combination of the registering table and the frame, the platen and the form block, and the driving shaft of a box covering machine, with the air impulse box supporting bar mounted in said frame, the air impulse box adjustably mounted on one end of said bar and arranged to be moved reciprocally between said table and said platen, and arranged to feed blanks from said table to said platen, the swiveling connection at the opposite end of said bar from said air impulse box, the cam mounted on said driving shaft and the lever connections between said cam and said swiveling connection arranged to impart an operative reciprocal stroke to said bar, and an air impulse box of sufficient throw to move a blank from said table to said platen, a bevel gear journaled to said frame and loosely mounted on and keyed to said rod and adapted to partially rotate it, said rod being reciprocally mounted on said gear, a second bevel gear journaled in said frame and in mesh with said rod's first named gear, said second gear being provided with a projecting arm, the outer end of which is pivotally attached to one end of a lever, the opposite end of said lever being pivotally attached to one end of a rock arm, the opposite end of which is pivotally supported by said frame, a roller mounted on said rock arm intermediate of its ends, and a cam mounted on said shaft provided with a cam groove in which said roller projects whereby a quarter

turning movement is imparted to said rod and air impulse box on its backward stroke of sufficient throw to avoid said form block.

13. In a pneumatically operating apparatus for feeding blanks to box covering machines, the combination of the blank, the blank receiving and registering table, and the box covering machine provided with a driving shaft, a blank receiving platen and a form block, with an air impulse box provided with air inlet apertures arranged and adapted to grip said blank by an air suction impulse and to release them by an air pressure impulse, means mounted on said shaft and including an air pump supported by said frame and connected by tubular connections to said air box, and including a cam, levers and other instrumentalities for creating an alternating air actuating suction and air pressure impulses at predetermined periods of time in said air impulse lever, a reciprocating rod arranged to adjustably support said air impulse box, and means including cams mounted on said driving shaft, and coöperating groups of levers, gears, and rock arms between said cams and arranged to be actuated thereby to impart to said reciprocating rod and air impulse box a reciprocal stroke that will move said air impulse box from said blank registering table to said platen under said form block, and that will return it to one side of said form block until clear of it and then move it into blank gripping relation to said blank registering table, said air pump being timed to grip said blank at said table by air suction and to release it when it is on said platen, by air pressure.

In testimony whereof I affix my signature in presence of two witnesses.

MELVILLE E. PETERS.
